UNITED STATES PATENT OFFICE

2,364,944

MACHINE GUN

Charles S. Brown, Syracuse, N. Y.

Application October 31, 1941, Serial No. 417,372

1 Claim. (Cl. 89—14.1)

This invention relates to machine guns, and has for its object an arrangement of the barrel of the gun, which is provided with heat conducting flanges, and an outer shell for bringing cooling air in contact with the flanges of the barrel and also an arrangement of the shell at the muzzle end of the barrel relatively to the barrel, or means beyond the muzzle end of the barrel to be impinged by the exhaust gases leaving the barrel and cushion or partly neutralize the recoil, and also to give a twisting or turning movement to the air around the path of the projectile as it and the exhaust gases leave the muzzle of the barrel.

It further has for its object a construction of the shell, barrel and frame or turret, whereby the barrel and the shell are readily assembled in and demounted from the frame or turret.

The invention consists in the novel features and in the combinations and constructions herein-after set forth and claimed.

In describing this invention, reference is had to the accompanying drawings in which like characters designate corresponding parts in all the views.

Figure 1 is an elevation of a machine gun embodying this invention.

Figure 2 is an enlarged longitudinal sectional view, partly broken away, of the barrel and contiguous part of the frame or turret.

Figure 3 is an enlarged end view of the muzzle end of the barrel and shell.

Figure 4 is an enlarged sectional view on line 4—4, Figure 2.

Figure 5 is a detail view showing in elevation the head at the muzzle end of the shell of the barrel.

Figure 6 is a view, partly broken away, of a wall of the frame or turret in which the head is mounted.

1 designates the frame or turret which is mounted on a suitable support or tripod 2, the frame housing the firing mechanism. With the exception of the feature hereinafter pointed out, the frame may be of any suitable size, form and construction.

The barrel includes a tubular core or body 3 and an outer body 4 of a metal having high heat conductivity, as an aluminum alloy. The inner tubular core or barrel proper is provided with peripheral more or less flexible flanges 5 extending circumferentially, circular or spirally around the same, and the outer heat conducting body 4 is integrally united to the flanged peripheral surface of the tubular core or barrel proper 3. In

practice, the heat conducting body is cast around the flanged tubular core, and in this way integrally united thereto. Owing to the flexibility of the flanges 5, the integral union is maintained during relative expansion and contraction of the outer body 4 of high heat conductivity, or in other words, there is no breaking away of the outer body 4 from the tubular core 3, due to difference in expansion caused by the difference of expansion coefficient of the different materials and of the heated temperatures. The outer body 4 is formed with circumferentially extending heat conducting flanges as 6. The outer diameter of the heat dissipating flanges 6 also taper from the breech end of the barrel toward the muzzle end.

7 designates an outer cylindrical shell enclosing the barrel and spaced therefrom forming an air space 8 around the barrel which on account of the tapering of the barrel increases in width toward the muzzle end of the barrel. The shell 7 is also provided with air inlets or ventilating holes 9 throughout its periphery. The shell projects at 10 beyond the muzzle end of the barrel 3 and the projecting portion 10 is provided with spiral blades 11 therein, these blades projecting from in the rear of the muzzle end of the barrel 3 beyond the muzzle end to the end of the shell 10. During the firing operation, the gases ejected from the muzzle end of the barrel 3 act to draw air through the openings 9 over the flanges 6 and eject said air at the muzzle end of the shell 10. The blades 11 are less than one convolution so as not to obstruct the flow of air or cause a back pressure thereof but give a twisting movement to the air about the path of the projectile where it leaves the muzzle end of the barrel 3 to the muzzle end of the shell 10, and thus avoid any retarding or deflecting effect of the air (being ejected from the shell) on the projectile. The spiral blades, due to the force of the gases thereon neutralize, to some extent, the recoil of the gun because of the axially outward force of the gases leaving the barrel acting on the spiral or 45 angular blades and cushion the recoil.

The shell 7 is mounted in the frame or turret 1 by means of a head 12 at the breech end of the barrel 3, the head 12 having an axial hub or nipple 13 formed with a bore 14 for receiving the breech end of the barrel 3 or in which the breech end slidably but closely fits, the breech end of the barrel 3 extending into the support for connection to or coaction with the gun mechanism. The head 12 is also formed with a radial slot 15 (see Figure 5) leading from the bore

14 through the periphery of the head 12. The front wall 16 of the frame or turret 1 is formed with a circular opening 17 into which the nipple 13 threads and with a radial slot 18 leading from the circular opening 17. When the parts are assembled, the slots 15 and 18 are in alinement. They are for the purpose of accommodating mechanism of the gun located for the most part within the frame or turret 1 to the rear of the wall 16.

In assembling, the barrel 3 including the tubular core or body 3 and the outer body 4 and 6 is mounted in the shell 7 through the breech end of the shell 7 when the head 12 is removed, this head 12 screwing into the breech end of the shell 7. The assembled barrel 3 and shell 7 is then screwed into the circular opening 17 of the front wall 16 of the frame or turret 1 and the parts of

the gun mechanism attached, some of these parts through the slots 15 and 18. The parts are demounted in the reverse order.

What I claim is:

10 A machine gun including a barrel, a cylindrical shell enclosing the barrel and having air holes therein throughout its length, the shell projecting beyond the muzzle end of the barrel and the projecting portion thereof being formed with internal spiral blades, each being less than one convolution of a spiral, all whereby the force of the exhaust gases ejected from the barrel acts to draw, injector fashion, air through the shell and the spiral blades impart a whirling motion to the injected air and to the gases mixed therewith coming from the interior of the barrel where the projectile leaves the barrel.

CHARLES S. BROWN.
